his ATTORNEY.

UNITED STATES PATENT OFFICE

2,582,621

ELECTRICAL CONNECTOR OF THE TROLLEY
TAP TYPEJohn Francis Conrad, Ebensburg, Pa., assignor to
Deltron Electric Products, Inc., Ebensburg, Pa.,
a corporation of Pennsylvania

Application May 1, 1950, Serial No. 159,335

2 Claims. (Cl. 173—273)

1

My invention relates to electrical connectors and is particularly useful in temporarily tapping electrical conductor wires or cables for the utilization of electrical current therefrom, for motors and other electrical devices.

One important field of usefulness for my invention as herein shown and described is in connection with underground mining equipment. The conventional feed line taps are made in such manner that when making a connection, the tap is put on the feed line cable without dislodging rock dust, coal dust or oxidation, which is invariably deposited on the cable by natural accumulation. Feed line cables under such circumstances offer a high resistance to the current flowing through such devices, and therefore, if such cables are not wiped clean the connection becomes highly heated, thus causing an appreciable drop in voltage which, in turn, is one of the reasons for inefficient machine operation.

One object of my invention is to provide a feed line tap of such form that it will wipe the conductor cable and automatically remove dust, rust or other foreign matter therefrom during positioning of the tap.

Another object of my invention is to provide a tap of the character referred to that can conveniently be employed in connection with a holder of the cartridge-fuse type and which can easily be adjusted to conductor cables of various sizes, and wherein the wiping effect referred to is automatically performed simply through the motions required to apply the tap to the cable.

As shown in the accompanying drawing, Figure 1 is a side view of the tap in partly assembled position on a cable; Fig. 2 is an edge view thereof, and Fig. 3 shows the manner in which the tap has complete engagement with the cable.

The tap or connector is here shown as having connection with a conductor cable or wire 5, for tapping current through a fused type holder 6 to a cable 7. The fuse 6 is provided with the ordinary insulated holder and has a threaded conductor stud projected therefrom for connection to the tap.

The stud 8 has threaded engagement with conductor jaws of laminated strip form bound tightly together at their lower ends by brass strips 9 and rivets 10, the assembled mass of strips being recessed and threaded for tight connection to the stud 8. These jaws are arranged in two opposed groups of strips 11 and 12, the strips of each group being preferably laminations of Phosphor bronze and copper that alternate with one another, and the Phosphor bronze serving as leaf springs. The groups are faced by conductor strips 13 in V-like formation that have direct engagement with the cable 5.

The conductor jaws are pivotally connected to

2

a block 14 by a stud 15 that extends through the laminated group and through the block, there being a spacing collar 16 interposed between the block and the group of strips.

5 The block 14 partly embraces hangers 17, here shown in the form of an inverted yoke, and is slideable vertically thereon for adjustment by a cap screw 18 that seats against the closed end or saddle of the yoke. The conductor strips 13 are thus adjustable to cables of various thicknesses.

10 In applying the tap, the hangers 17 will first be hung upon the wire or cable 5 and the fuse holder 6, together with the blades 11-12 swung toward a vertical position. During this movement, the contacting strips 13 will wipe the cable 5, to clean the same, for good electrical contact as above mentioned. The movement of the blades 13 in an arcuate path that extends somewhat in the same general direction as the cable makes for more effective cleaning of the cable than if the conductor jaws were applied in a vertical direction from either above or below the cable.

15 The block 14 will be adjusted so that the upper ends of the conductor jaws will be sprung apart slightly as shown in Fig. 3, to thereby insure tight engagement with the cable 5.

I claim as my invention:

20 1. An electrical connector of the trolley tap type, comprising a holder, yieldably-opposed conductor jaws carried thereby, a pair of hanger members for hooked engagement with an electrical line, a block adjustable longitudinally of the hanger members, and a pivotal connection between the jaws and the block, on an axis generally transverse to a conductor on which said hanger members are suspended, and at such elevation that the jaws may have wiping engagement with a line engaged by the hanger members.

25 2. A connector as recited in claim 1, wherein the hanger members are in the form of an inverted yoke that has hooks on its upper extremities and the said block is adjustably supported on the saddle portion of the yoke.

JOHN FRANCIS CONRAD.
